(57) **CLAIM**

The ornamental design for an electric self-balancing scooter, as shown and described.

DESCRIPTION

FIG. 1 is a top, front, right side perspective view of an electric self-balancing scooter showing the claimed design; FIG. 2 is a front elevational view thereof;

FIG. 3 is a rear elevational view thereof;

FIG. 4 is a left side elevational view thereof, wherein the right side view is omitted because the right side view is identical to the left side view;

FIG. 5 is a top plan view thereof;

FIG. 6 is a bottom plan view thereof; and,

FIG. 7 is a bottom, rear, left side exploded perspective view thereof.

The broken lines in the drawing depict portions of the electric self-balancing scooter that form no part of the claimed design.
